[57] ABSTRACT

A therapeutic composition comprised of an aqueous medium containing about 75-150 millimoles of Na^+ , about 5-50 millimoles of K^+ , about 5-50 millimoles of HCO_3^- , about 75-150 millimoles of Cl^- and preferably containing about 1-30 millimoles of Mg^{++} and about 1-30 millimoles of HPO_4^{2-} and/or SO_4^{2-} ; the solution having a pH of about 6.8-8.2 and an osmolality of about 170-460 and preferably about 260-340 and more preferably 290-310. The solution can be administered orally but preferably parenterally. Also, the anhydrous form of the composition in a tablet form as well as an oral composition containing flavoring agents is taught.

11 Claims, No Drawings

THERAPEUTIC COMPOSITION

BACKGROUND OF THE INVENTION

After accidental or elective operative injury to human patients, there occurs a decrease in the hemoglobin concentration, an elevation of the erythrocyte sedimentation rate of peripheral blood, and a loss of red blood cells (RBC) from the effective blood volume. These events are recognized as anemia. Also, immediately subsequent to the injury the white cell count is usually elevated, and the thrombocyte count is decreased, implicating pancytic mechanisms.

5 solution has enhanced water retention significantly, as evidenced by consistent gain in weight during operation when saline is administered. Complimenting normal saline solutions with potassium and calcium in concentrations equivalent to plasma water (10 mEq/L, total) has had little additional effect. Hence, the addition of ions to sterile water in quality and at concentrations approximately those in blood water has not significantly reduced anemias observed from the use of sterile water alone.

10 Examples of parenterally administrable preparations in current use are:

Solution	Approximate pH	Cations (meq./L)					Anions (meq./L)			
		Na	K	Mg	Ca	Cl	Phosphate	HCO ₃	Acetate	Glucconate

The administration of whole blood is useful to rectify the pancytic changes. However, most surgeons have been unable to maintain adequate quantities of peripheral total hemoglobin, red blood cells, and thrombocytes through the use of whole blood, even when quantities far in excess of that lost by bleeding are infused. Also, the collection and storage of whole blood generally produces a hyperosmolar, acidic water solution, as a result of the changes in RBC and blood water during collection and storage. Furthermore, whole blood is expensive, and may produce unwanted immunological responses in the recipient.

The surgeon and anesthesiologist generally have four other choices, i.e., instead of whole blood infusion, to correct these adversities. These are administration of (1) plasma, (2) separated (packed) erythrocytes, (3) synthetic water solutions, or (4) synthetic water solutions containing synthetic protein. Plasma has some of the disadvantages of whole blood. Separated erythrocytes, besides being expensive, have the disadvantage of decreases in functional and structural life after reinfusion. In recent years, synthetic water solutions, with or without protein, have been used to re-establish normalcy in peripheral vascular volumes and for maintenance of blood pressure.

The development of synthetic water solutions in the prior art has emphasized ionic content, particular sodium chloride, with little regard to other physicochemical requirements. Such thinking is still current. The most recently introduced water solutions beg their use through ionic contents equivalent to plasma water as the latter appears during health. Also, the blood water of patients, receiving a multitude of new anesthetic agents and adjuvants and subjected to operative techniques of increasing complexity, is exposed to body water infusates which are at variance, frequently extreme, with the physicochemical content in health.

Altering ionic content of water solutions has not provided the water environment considered optimal during elective or traumatic operative therapy. Furthermore, synthetic water solutions should provide support to the patient in excess of maintenance of blood water volume. Water for injection, sterile, U.S.P., may be used to replace or expand blood water lost during elective or accidental trauma, if the sole purpose of administered water solution is the replacement of water losses. However, the anemia or injury is more intense in the post-operative period after use of sterile water or of other similar hypo-osmolar solutions, resulting in prolonged morbidity, particularly in post-operative hospital time, and accounting for the more frequent use of whole blood before, during, and after operation.

The addition of sodium chloride to sterile water, in so-called isotonic concentration (154 mEq/L [milliequivalents/liter]), has reduced only minimally the post-operative anemia. Such a

30 Certain of these solutions are compared in specific tests with applicant's aqueous solution.

SUMMARY OF THE INVENTION

35 Applicant has discovered a therapeutic composition, preferably administered parenterally, to overcome at least most of the disadvantages of similar aqueous solutions in the prior art. The formulation is based on the mean solute values in extracellular water (referred to herein as ECW) and is designed to minimize water movements into fixed cells after operative, anesthetic and accidental trauma. Also, Applicant's parenteral solution diminishes loss of functional decrements in all body systems, particularly heart and circulating fluids, lung, kidney, gastrointestinal tract and brain. Applicant's composition is useful in tablet form, oral dosage form containing flavoring agent, etc.

DESCRIPTION OF THE PREFERRED EMBODIMENTS

40 45 Applicant's therapeutic composition is preferably iso-osmolar with respect to the mean osmolality of ECW. The mobility of the ions is preferably maximal in the ECW to minimize ICW (intracellular water) depletion or overload. Also, the water content is preferably representative of the 50 ratio of water to solute loss during the operative procedure or trauma or imbalance.

55 In extracellular water, the major cations are H⁺, K⁺, Na⁺, Ca⁺⁺, and Mg⁺⁺ whereas the major anions are OH⁻, HCO₃⁻, Cl⁻, SO₄²⁻, HPO₄²⁻, and IOA ("impermeable" organic anions). The relative size of the hydrated ions, as referenced to K⁺, and the velocity of each ion in water, in a uniform electrical field, are:

60	Velocity of solute ion under gradient of one Solute Solute volt/cm (univalent ion)	Relative diameter	
		cation anion or 0.5 volt/cm (divalent)	of solute ion, Angstroms
70	H ⁺ 315	0.20	
	K ⁺ 64.2	1.00	
	Na ⁺ 43.2	1.49	
	OH ⁻ 173	0.37	
	HCO ₃ ⁻ 133	0.72	
	Cl ⁻ 65.2	0.98	
	IOA 35	1.84	
	SO ₄ ²⁻ 34	1.89	
	HPO ₄ ²⁻ 28	2.29	
75	Ca ⁺⁺ 25.5	2.51	
	Mg ⁺⁺ 22.5	2.84	

The mobility coefficient of each ion in dilute water solution is dependent upon the size of the hydrated ion and upon its velocity under a uniform electrical gradient. Changes in solute content, pH, and osmolality affect the mobility coefficients. The Mg^{++} , HPO_4^- and SO_4^- ions are implicated as components of intercellular water or interstitial water substrates during glycolysis and oxidative reaction sequences in energy metabolism.

Applicant's parenteral solution contains sodium (Na^+) and potassium (K^+) as the principal major cation solutes, and bicarbonate (HCO_3^-) and chloride (Cl^-) as the primary anion solutes. These were selected because their coefficients of mobility, with hydrogen (H^+) and hydroxyl (OH^-), are maximal with respect to all other solutes, in any given situation. Magnesium (Mg^{++}) was selected as the principal minor solute cation, and phosphate (HPO_4^-) and/or sulfate (SO_4^-) as the principal minor solute cation. The Mg^{++} , HPO_4^- and SO_4^- ions assist in stabilization of solute velocities, hence distribution, in the extracellular water and/or the intercellular water. The concentration of the ions in applicant's aqueous solution are given in millimoles as:

Min-Ion imum	Max-Preferred	Most Preferred
Sodium (Na^+) 75	150 85-140	128
Potassium (K^+) 5	50 10-40	17
Magnesium (Mg^{++}) 1	30 2-20	5
Phosphate (HPO_4^- , or 1	30 2-20	5
Sulfate (SO_4^- ,		
Bicarbonate (HCO_3^- , 5	50 10-40	25
Chloride (Cl^-) 75	150 85-130	120

The administrable solution can have an osmolality (defined as the specific number of millimoles dissolved in one liter of water) within the range of from about 170 to about 460, preferably from 260 to 340, more preferably from 290 to 310 and most preferably about 300. The pH can range from about 6.8 to 8.2 and preferably is within the range of 7.4 to 8.0 and more preferably about 7.6 to about 7.8. It is not necessary that the Mg^{++} , SO_4^- , and HPO_4^- be present but it is preferred where stabilization of solute velocities, thus distribution, is desired in the ECW and/or ICW. Known water soluble salts containing the above ions are useful to make up the solution in U.S.P. water. Examples of such salts include $NaCl$, KCl , $NaHCO_3$, $KHCO_3$, $MgCl_2$, Na_2SO_4 , Na_2HPO_4 , $MgSO_4$, and K_2HPO_4 .

A preferred composition for parenteral administration is one containing about 25 millimoles of $NaHCO_3$, about 17 millimoles of KCl , about 103 millimoles of $NaCl$ and about 5 millimoles of $MgSO_4$.

Solutions having an osmolality less than about 290 can be designed to move into the cells; thus, such solutions are useful in treatment of heat stroke or situations causing excessive sweating. However, if the osmolality desired is in excess of about 310, the solution can be designed to attract water out of the cells. As a result, such solutions are useful, for example, in the treatment of overdoses of barbiturates or any situation resulting in an unusual accumulation of water within the cells.

The pH of the solution is desirably about 6.8 to about 8.2. Such pH is preferably obtained by using the appropriate salts taught within this invention and such solution will be highly buffered against pH changes. Adjustment of the pH can be obtained, if desired, with known acids or bases, e.g., HCl , $NaOH$, etc. whose reactions with the solution will not produce ion solutes different from those specified.

The solution is preferably administered parenterally; but, it can be administered orally. Where oral administration is desired, the salt components are desirably chosen to eliminate objectionable taste of the solution. For example, KCl can impart a bad taste. A more acceptable solution from the standpoint of taste is one containing $KHCO_3$, $NaHCO_3$, $MgCl_2$, and Na_2SO_4 . Flavoring agents, e.g., orange flavoring, etc. and

pharmaceutically acceptable vitamins in dosage form compatible with applicant's composition can be incorporated. For example, vitamin C is useful where the solution is taken orally. Other additives pharmaceutically acceptable and compatible with applicant's composition can also be incorporated.

Also, the appropriate amount of cations and anions can be contained in the anhydrous form as well as a concentrated hydrous form. The hydrous form can be at a concentration more than the desired osmolality and, before administration, it can be diluted to the desired osmolality. By containing the solution at a high ion concentration, shipping charges, storage costs, etc. can be reduced.

Regarding the anhydrous form, the appropriate salts and the desired amounts of salts can be contained in a protective container (a pharmaceutically acceptable container) so that convenient dilution to the desired volume and at the desired place of usage can be obtained. Also, the salts can be compressed in a uniform mixture and can optionally contain an inert diluent, e.g., binder. Thus, the salts can be embodied in a tablet suitable for dilution and eventually oral administration.

The tablet binder is a pharmaceutically acceptable binder and is preferably one that produces minimum osmotic effects and is one that is not ionized. Examples of useful binders include nonionic detergents such as Pluronic F-68 (trademark of Wyandotte Chemicals Corp., defined as a condensate of ethylene oxide with a condensate of propylene oxide and propylene glycol) and similar nonionic detergents, preferably having molecular weights above about 8,000. Also, the tablet can contain pharmaceutically acceptable effervescent agents such as citric acid, tartaric acid, etc. Where the salts are in the anhydrous form, the concentration of the ions can be (mole %):

35	Ion Range	Preferred Range	Most Preferred Range
	Na^+ 46.3-32.6	44.0-35.9	42.7
40	K^+ 3.1-10.9	5.2-10.1	5.7
	Mg^{++} .6-6.5	1.0-5.1	1.7
	HPO_4^- .6-6.5	1.0-5.1	1.7
50	SO_4^- .6-6.5	5.2-10.1	8.3
	HCO_3^- 3.1-10.9	44.0-33.4	40.0
	Cl^- 46.3-32.6		

Where the Mg^{++} and HPO_4^- and/or SO_4^- ions are absent, the molar composition can be about 37.5-46.9% Na^+ , about 3.1-12.5% K^+ , about 3.1-12.5% HCO_3^- , and about 46.9-37.5% Cl^- . But, preferably, the Mg^{++} and HPO_4^- and/or SO_4^- are present.

Applicant's solution is preferably administered to mammals before operation, during anesthesia, during operation and after operation or trauma. Desirably, it is administered in quantities calculated to replace water and osmolar losses in the ECW. Excessive administration of the solution can be tolerated by the mammal, however, over-expansion of the ECW can modify mobile cell mobilization. Preferably, the solution is administered before trauma and in amounts calculated to replace water and osmolar losses in the ECW. Where administered before operation and before anesthesia, it is preferably begun about 2 hours prior to anesthesia.

Proper administering of applicant's solution, *inter alia*, can have the following benefits:

1. iso-osmolar expansion of ECW with predictable equilibration of administered water between circulating water volume and ISW space components of ECW;
2. as a result of (1), a high tolerance of unplanned overloading of the circulating water volume—thus hypertension, cardiac pulmonary failure and coma can be reduced;
3. as a result of (1), maintenance of suspension indices of solutes, e.g., mobile cells, lipids, and proteins, in ECW is obtained;
4. as a result of (1) and (3), iso-osmolar expansion of large solutes in ECW is obtained;

5. as a result of (4), minimization of mobile cell destruction (particularly red cell) and of intravascular aggregation of cells is obtained—both of which otherwise follow planned or unplanned trauma;

6. as a result of (1), enhancement of perfusion of tissues during elective, operative, and anesthetic trauma, with or without prior accidental trauma, is reduced.

Other benefits are obvious after the specification and claims are read and fully understood.

The following examples are presented merely to teach specific working embodiments of the invention. Equivalents and uses, obvious to those skilled in the art, are intended to be incorporated within the invention as defined in the specification and appended claims.

EXAMPLE

Mongrel canines having a mean weight of 15 kgm were operated on under pentobarbital sodium anesthesia for bilateral placement of ligatures about the renal pelvi and/or for splenectomy. Seven days after operation, these animals were exposed to either water loading or water deprivation test, as indicated below. The aortic blood pressure, the hematocrit (HCT), blood water volume (BW), and extracellular water volume (ECW) were determined before and after either loading or deprivation, and at indicated times. Where a control patient is used, neither loading nor deprivation was effected and a lapse of time equal to the same lapse for either loading or deprivation was allowed for the after determination. Where loading experiments were done, 30 minutes was allowed between the determinations. In depletion experiments, determinations were made immediately after hemorrhage, at 2 hours past hemorrhage, and at 5 days past hemorrhage. The BW was measured with T-1824 dye, also defined as Evans blue dye; 30 minutes was allowed for equilibration of the dye. HCT was determined from multiple arterial and venous microhematocrit determinations (corrected for trapped

All solutions were prepared on the day of use after careful weighing of dried reagents and addition of sterile water for injection, U.S.P., to 1,000 milliliters. Sterilization was accomplished by autoclave, after which a 5-milliliter aliquot of each was removed and analyzed for solute content, osmolality, pH and sterility. After evaluation, ligatures were removed, incisions closed, and animals returned to their cages.

Deprivation Tests

10 Fifteen canines to each of five series were observed during water deprivation of the ECW by hemorrhage at 47 percent of the TBV. In one series, no replacement water solution was administered, and, as reported in Table I, no animals survived 24 hours; these animals expiring secondary to cardiac and pulmonary arrest. In four additional series, Applicant's solution (U.S.P. water containing 25 millimoles of NaHCO₃, 17 millimoles of KCl, 103 millimoles of NaCl and 5 millimoles of MgSO₄, osmolality = 300 pH = 7.6-7.8) and certain other 15 water solutions were infused singly into the canines at the onset of ventricular fibrillation and cardiac arrest. The infused quantities were equal to the shed blood volume. Survival was 20 100 percent in animals receiving applicant's solution, with a mobilization of an additional 16 percent of RBC. Survival was 25 reduced markedly in all animals receiving other water solutions. Regarding other water solutions, enhancement of TBV was best with sodium chloride, but pH and RBC decreases contributed to low survival. Similarly, pH and RBC alterations by other water solutions decreased survival. Furthermore, 30 there is no statistical difference between animals receiving either no water replacement or either lactated Ringer's solution or Normosol-R. These results are reported in Table I.

TABLE I

35 Comparison of applicant's solution with other water solutions (all values 1 hour after replacement of water solution equal to shed blood volume)

TABLE I

Condition	TBV	HCT	RBC	BW	ISW	ECW	Percent mortality, 24 hours

*Percent of steady state.

**mO./L. = millimoles/liter.

plasma) and was related to the true or "total body" hematocrit by the ratio 0.85—this ratio was empirically measured by comparing direct red cell volume and blood water measurements in 25 canines. Red cell mass (RBC) was calculated from the hematocrit and blood water volume. ECW was measured with radiobromium, Br-82, 2 hours was allowed for equilibration of the isotope. Interstitial water (ISW) was determined as the difference between ECW and TBV. Osmolality was determined by commercial osmometer. Specific gravities of all water solutions either added or removed were determined, thus specific correlations were established between the weight of either added or removed fluids. The partial pressure of water vapor in the ambient air was adjusted to the partial pressure of water vapor in the expired air of the animal under evaluation. During loading, the ligatures were tightened about the renal pelvi. Therefore, after the 30 minute interval for distribution of added water solutions, during the 2 hours allowed for equilibration of isotope and 30 minutes for equilibration of the dye, water losses from the animals were minimized.

Effect of Varying Osmolalities of Applicant's Solution During Water Deprivation

60 Table II indicates the effect of varying the osmolality of applicant's solutions (pH = 6.8-8.2) upon the mortality of canines after water deprivation through hemorrhage of 47 percent of steady state TBV. A 47 percent hemorrhage was sufficient to produce death in 100 percent of the canines in the absence of injection of parenteral fluids. The replacement of applicant's solution is equal to shed blood:

TABLE II

Osmolality of infused solution (millimoles/liter)	Mortality percent	RBC Mass after infusion	Percent of a TBV after 47% Hemorrhage
460	15	—10	
340	15	—10	
310	Zero	+4.0	
300	Zero	+15	
290	Zero	+2.5	
260	25	±1.5	
170	25	—7	

The above data clearly indicates basis for preferred osmolality ranges, especially the 290-310 range.

Establishment of pH Range

Five canines to each of 10 series were observed during separate water deprivation tests of hemorrhage of 47 percent of TBV. The exact quantity of shed TBV was replaced at the onset of cardiac arrest with sodium chloride and sodium bicarbonate mixtures at pH in range of from 5.5 to 8.8 although these solutions are not the same as applicant's solution, these data obtained are applicable with their invention. The critical pH established with minimum mortality, i.e., no mortality, is from 6.8 to 8.2.

Water Loading

Each of 15 canines in three different series were observed during water loading with (1) aqueous solutions of sodium chloride, (2) aqueous solutions of sodium bicarbonate and (3) applicant's aqueous solution containing 25 millimoles of NaHCO₃, 17 millimoles of KCl, 103 millimoles of NaCl and 5 millimoles of MgSO₄. The mean ECW of the canine = 3,000 ml. Results of the tests are given in Table III:

TABLE III

mO./L.	Water solution administered		ECW after infusion		mO./L.	ECW	Percent water volume	TBV percent increase or decrease
	Volume, ml.	Total, ml.	Percent increase water volume	Percent change osmolality				
A. Aqueous solution of sodium chloride								
290.....	600	3,610	20.3	-0.66	298	0	Decrease 5.2.	
300.....	600	3,605	20	-0.45	299	0	Decrease $\pm$ 1.2.	
310.....	600	3,798	26.6	-1.66	295	6.6	Decrease 6.4.	
B. Aqueous solution of sodium bicarbonate								
290.....	600	3,625	20.8	-0.71	297	0	Decrease 1.6.	
300.....	600	3,656	21.5	+0.15	302	0	Increase $\pm$ 1.5.	
310.....	600	3,710	23.4	+0.15	301	3.6	Decrease 3.3.	
C. Applicant's aqueous solution								
300.....	600	3,600	20	0	300	0	Increase 20.	

The above data indicate that with applicant's solution the ECW was expanded by the same increment as the load and there was neither an increase nor decrease in osmolality. Also, the RBC component of TBV was increased by same percentage as was the ECW, hence BIW was expanded in identical manner, 20 percent, such that TBV was increased 20 percent.

Comparison with Other Water Solutions During Loading

Applicant's solution was compared with other water solutions at 30 minutes after canine water loading. The loading was equal to 100 percent of TBV. Data are presented in Table IV:

each produced dislocations of water and solutes and reduction in RBC as compared to applicant's solution (identified in "Water Loading" tests, osmolality = 300).

TABLE V

Water loading (% of TBV)	Condition Blood Pressure Increase (%)		Blood Pressure Decrease (%)	BIW Increase (%)
	Aortic	Femoral		
10 2.3		1		25
20 3		8		11
30 8		15		35
Water Deprivation (% of TBV through hemorrhage)				
10			2.0	2
20			3	4
30			5.0	9.5
20 35			60	
47			77	10
			9.3	18

Effect on Blood Pressure With Applicant's Solution

During water loading and water deprivation tests, the effect on the aortic and femoral blood pressures were observed. Results of these tests are indicated in Table V. Applicant's aqueous solution is identical to the one identified in "Water-Loading" tests.

Loading at Different Osmolalities and pH

Loading of ECW with applicant's solution at different

TABLE IV

Condition	TBV	HCT	RBC	BIW	ISW	ECW	Percent Mortality at 24 hours
Steady State Before Loading	1100	44	485	615	3900	5000	
After Applicant's Solution	1320	44	585	735	4800	6120	Zero
pH 7.6 300 mO/L	*	+20	-	+20	+23	+20

What is claimed is:

1. An injectable aqueous solution comprising about 75 to about 150 millimoles of sodium cation, about 5 to about 50 millimoles of potassium cation, about 5 to about 50 millimoles of bicarbonate anion and about 75 to about 150 millimoles of chloride anion and having a pH of about 6.8 to about 8.2 and an osmolality of about 290 to about 310.
2. The composition of claim 1 wherein the pH is about 7.4 to about 8.0.
3. The composition of claim 1 wherein the osmolality is about 300.

4. The composition of claim 1 wherein about 1 to about 30 millimoles of magnesium cation and from about 1 to about 30 millimoles of phosphate and/or sulfate anion are incorporated into the composition.

5. The aqueous solution of claim 1 wherein there is incorporated about 1 to about 30 millimoles of magnesium cation.

6. The aqueous solution of claim 1 wherein there is incorporated about 1 to about 30 millimoles of phosphate anion or sulfate anion or a combination of phosphate and sulfate anions.

7. The aqueous solution of claim 1 wherein the osmolality is about 300.

8. The aqueous solution of claim 1 wherein the pH of the solution is about 7.4 to about 8.0.

15 9. An injectable aqueous solution comprised of about 85 to about 140 millimoles of sodium cation, about 10 to about 40 millimoles of potassium cation, about 2 to about 20 millimoles of magnesium cation, about 85 to about 130 millimoles of chloride anion, about 10 to about 40 millimoles of bicarbonate anion and about 2 to about 20 millimoles of phosphate and/or sulfate anion(s) and the solution having a pH within the range of about 6.8 to about 8.2 and having an osmolality within the range of about 290 to about 310.

10 10. The aqueous solution of claim 9 wherein the pH is within the range of about 7.4 to about 8.0.

11 11. An injectable aqueous solution comprised of about 103 millimoles of sodium chloride, about 25 millimoles of sodium bicarbonate, about 17 millimoles of potassium chloride, and about 5 millimoles of magnesium sulfate and having a pH within the range of about 7.6 to about 7.8.
